UNITED STATES PATENT OFFICE

2,560,654

DEVICE FOR DRESSING GRINDING WHEELS

Floryan Lohutko, Detroit, Mich., assignor to The
Thompson Grinder Company, Springfield, Ohio,
a corporation of Ohio

Application December 14, 1948, Serial No. 65,257

2 Claims. (Cl. 125—36)

1

This application relates to a dressing tool for grinding machines, and particularly to an improved type of dressing tool composed of a plurality of individual elements.

Grinding wheels are usually dressed by a diamond cutting device or by a crush dressing roller. Each of these devices has certain limitations thereon as, for example, the smooth finish obtained on the wheel by a diamond dressing tool which materially decreases the cutting speed of the wheel, and the difficulty of forming a crushing roller to the exact shape desired and maintaining it within predetermined limits over a number of dressing cycles.

The primary object of the present invention is to provide a grinding wheel dresser which can be made very accurately and which will retain its accuracy for a long period of time.

Another object is to provide a device for dressing a grinding wheel which will provide for a highly accurate wheel and one which has a very rapid cutting action.

These and other objects and advantages will become more apparent upon reference to the following description taken in connection with the accompanying drawings in which:

Figure 1 is a perspective view of a portion of a typical grinding machine showing the grinding wheel and a dresser according to this invention associated therewith;

Figure 2 is a fragmentary section of the wheel and as indicated by the line 2—2 on Figure 1;

Figure 3 is an enlarged side view of a dressing tool constructed according to this invention;

Figure 4 is a vertical section taken through a modified form of the dressing device;

Figure 5 is a perspective view of a portion of the device shown in Figure 4 illustrating the arrangement of the individual dressing members therein; and

Figure 6 is a fragmentary view showing a modified form of individual dressing member.

Referring to the drawings, the grinding machine shown therein comprises a reciprocable work holding table 10, and associated therewith is a grinding wheel 12 mounted on the shaft of a drive motor 14. The wheel may be adjustable in the usual manner relative to the table in order to properly present it to a workpiece mounted thereon.

Also mounted on the table 10 and at one end thereof is a frame 16 which rotatably supports a drum like dressing member 18. This dressing member is adapted for being driven in rotation as

2

by the drive motor 20 connected with the supporting shaft of the dressing member by belting, gearing, or the like contained within the housing 22.

5 The dressing member 18 mounts around its periphery a plurality of individual elements 24 and which are better illustrated in Figures 3 and 4. These individual elements comprise end parts as at 26 of sintered material containing silicon carbide and preferably include a predetermined amount of diamond dust or diamond grit.

As is well known, work members formed of silicon carbide and fusible powdered material, as for example, powdered metals, carbon and resin 15 or like binder, can be shaped in a suitable die and sintered to a very exact shape. Such treatment is the basis of many products, such as "Carboly" and "Stellite" cutting tools. By so shaping the individual elements they can be 20 formed to a very exact size and by incorporating diamond dust or diamond grit therein can be made to have a very fast cutting action on a grinding wheel.

The sintered end parts 26 are carried on the 25 tapered shank 28, and the tapered shank is adapted for being received in a tapered bore 30 in a peripheral flange part 32 of the dressing member 18. Cap screws 34 provide the means for retaining the individual dressing elements in their respective tapered bores.

The dressing member in Figure 1 is shown as having a single row of individual dressing elements therearound and thus can be employed for dressing a wheel to the shape shown in Figure 2 wherein a single groove 36 is formed around the periphery of the wheel. However, a plurality of rows of individual elements may be mounted in the dressing member as shown in Figure 4, and the device can thus be utilized for forming a plurality of annular grooves around the wheel.

40 It will be understood that the grooves referred to above could be annular or could be spiral around the wheel in the manner of a thread. The particular form of groove is determined by relative movements between the wheel and dressing member during the dressing cycle.

In utilizing the dressing device both the wheel and the dressing device are driven, but at different peripheral speeds. The wheel is then moved into 45 engagement with the dressing device and its periphery is formed thereby as the dressing member rotates and carries the individual elements into cutting engagement with the wheel.

It will be noted that the individual elements not 55 only cut the wheel due to the diamond grit par-

ticles in the said elements, but also provide a picking action, by means of which the bonding of the wheel is crushed, thereby preventing the wheel periphery from being too smooth and slow cutting.

Due to the aforementioned picking action, which would cause a certain radial impact on the individual dressing elements, it may be desirable to provide each thereof with a shoulder as indicated at 38 in Figure 6, and which shoulder will provide for positive radial positioning of the individual dressing elements.

A dressing tool constructed of individual dressing elements according to this invention provides for a very rapid dressing action and results in a sharp wheel which is highly accurate in configuration and therefore produces accurately shaped workpieces.

It will be understood that this invention is susceptible to modification in order to adapt it to different usages and conditions and, accordingly, it is desired to comprehend such modifications within this invention as may fall within the scope of the appended claims.

I claim:

1. In a dressing tool for grinding wheels, a rotatable wheel having an axially projecting annular peripheral flange, radial inwardly tapered and co-planar bores equally spaced around the circumference of said flange, tool members having abrasive heads of a sintered material containing silicon carbide extending radially from said flange and tapered body portions supporting said abrasive heads, said body portions being seated in one end of said bores, fastening means extending into said bore from the opposite end of said bores

and detachably holding said tool members in said bores.

2. In a dressing tool for grinding wheels, a rotatable wheel having an axially projecting annular peripheral flange, a plurality of rows of radial inwardly tapered and co-planar bores equally spaced around the circumference of said flange, tool members having abrasive heads of a sintered material containing silicon carbide and diamond grit extending radially from said flange and tapered body portions supporting said abrasive heads, said body portions being seated in one end of said bores, and fastening means extending into said bore from the opposite end of said bores and detachably holding said tool members in said bores.

FLORYAN LOHUTKO.
